CLAIM

The ornamental design for a freestanding cabinet, as shown and described.

DESCRIPTION

FIG. 1 is a perspective view of a first embodiment of a freestanding cabinet showing my new design;

FIG. 2 is a front elevational view thereof;

FIG. 3 is a left side view thereof, the opposite side being a mirror image of the side shown;

FIG. 4 is a perspective view of a second embodiment of a freestanding cabinet; and,

FIG. 5 is a front elevational view thereof.

The broken lines are for illustrative purposes only and form no part of the claimed design.
